HANGER FOR TROUSERS

Endy Anderson, Brooklyn, N. Y.

Application May 21, 1958, Serial No. 50,995

Term of patent 3½ years

(Cl. D80—8)

I claim:

The ornamental design for a hanger for trousers, substantially as shown.
